UNITED STATES PATENT OFFICE.

ALONZO DURKEE, OF NEW YORK, N. Y., ASSIGNOR TO MOSES HARRIS, OF SAME PLACE.

MECHANICAL MUSICAL INSTRUMENT.

SPECIFICATION forming part of Letters Patent No. 251,846, dated January 3, 1882.

Application filed May 12, 1881. (No model.)

To all whom it may concern:

Be it known that I, ALONZO DURKEE, of the city, county, and State of New York, have invented a new and useful Improvement in Musical Instruments; of which the following is a full, clear, and exact description.

This invention relates to wind-instruments which are manually operated upon or are mechanically played or controlled by means of one or more strips or sheets of paper or other suitable material perforated to represent the different notes or sounds it is desired to produce and caused to automatically pass over air-ducts, and thereby control the action of the valves which determine the admission of air to the reeds or pipes of the instrument, whereby said reeds or pipes are made to produce musical sounds.

In certain mechanical musical instruments of this character the perforated sheets or strips are made to control the action of the valves or keys by means of a series of jacks, levers, or key-moving fingers arranged on one side of said strip or sheet to operate through the perforations of such strip or sheet upon a series of push-pins or key-moving rods arranged on the opposite side of said strip or sheet; but this combination of devices is lacking in an essential element, which would greatly enhance its value by making it operate with invariable accuracy. It is found if the perforated sheet or strip from any cause fail to run truly, or if the jacks or levers have any lateral movement whatever, that the noses of the said jacks will not fall through the perforations in the said strip or sheet, but will, on the contrary, in such contingencies remain resting on the said strip as it passes beneath them, and thereby fail to move the push-pins to operate the valves, or, if they do pass through said perforations, will fail to fall upon the heads of the push-pins.

This invention consists in combining with the said jacks or levers and push-pins or key-moving rods a laterally-moving perforated block or bar, that holds the upper ends of the push-pins in its perforations and at the same time embraces the edges of the perforated sheet or strip, so that when the said sheet or strip moves laterally the said block or bar will move synchronously with it, holding the push-pins

in their proper relative positions with the perforations in said strip or sheet; and the invention further consists, in combination, with the pressure-chamber and the sound-producing devices, of novel bellows-valves arranged to close by expansion from inward spring and air pressure against the sound-board bar, and thus shut off the air from the sounding pipes or reeds, and to open the air-passages to them by collapse under exterior air-pressure; and it consists, further, in combination, with said pressure-chamber and bellows valves or pallets, of double-action disk-valves, that determine or regulate the communication between the pressure-chamber and the interior of the bellows valves or pallets and between said bellows valves or pallets and the open air, said disk-valves being operated by suitable levers.

Figure 1 is a partly-sectional front elevation, showing my improvements applied to a pipe-organ, on line *x x*, Fig. 2. Fig. 2 is a sectional elevation of the organ on line *y y*, Fig. 1. Fig. 3 is a partial sectional side elevation on line *z z*, Fig. 1. Fig. 4 is a partial sectional plan view on line *w w*, Fig. 1.

Similar letters of reference indicate corresponding parts.

In the drawings, A represents the sounding-board, from which projects at right angles the fixed rail A', through which are vertical tubes or perforations *a*, in which the push-pins B move up and down. In the top of this rail A' is a groove or mortise, *b*, in which is fitted the bar or block C, so that it can easily slide laterally. Into the perforations *c* in the said sliding block C the heads of the push-pins B are entered, so that they may move with the said moving block C. The raised edges *c'* on the ends of the block C are far enough apart to admit between them the perforated music sheet or strip D, which rests upon and is designed to be drawn over the face of the said block C, being rolled upon one drum D' and from the other drum D' in the ordinary manner. The width of said strip or sheet D is so nearly the same as the distance between the block-edges *c'* that if said sheet or strip D, in passing over the said block C, deviates laterally in the slightest degree it will move said

block C with it, and consequently the heads of the push-pins B, so that the perforations *c* in the block C and the push-pins B will always be preserved in the same relative positions with 5 the perforations in the strip or sheet D.

E E are jacks, levers, or key-moving fingers, the rear ends of which are pivoted, as shown at *d*, in a vertically-moving frame, E', that swings on a pin, *d'*, extending from the sound-board A. The front ends of these jacks or levers E E are provided with downwardly-projecting noses *f*, that are designed to rest on the strip or sheet D, directly over the perforations *c* of the block C, so that as said strip or sheet D is moved along the noses *f* of said jacks or levers E fall by their own gravity through the perforations in said sheet or strip D upon the tops of the push-pins B, and cause the latter to operate to open the valves that 10 regulate the admission of air to the sounding devices. To cause these jacks or levers E E to also preserve a constant relative position to the perforations in the perforated music-strip D and to the push-pins B, the box or frame E', 15 in which the said jacks or levers E E are pivoted, is provided on either side with downward-projecting ears *f'*, whose inner surfaces when the said frame E' is down in position shown in Fig. 1, are in contact with the edges 20 of said music-strip D, so that the jacks or levers E and frame E', as well as the sliding block C and tops of the push-pins B, are moved laterally by and with the said strip D, and hence always preserve the same relative positions with each other laterally, so that the correct and effective action of each one of the parts is assured. A stud, *f*², projecting from the sounding-board A, limits the downward movement of the frame E'.

When the instrument is in operation as a simply mechanical instrument the falling of the jacks or levers E upon the push-pins B causes the latter in their turn to depress the levers F, that are pivoted on a post, F', and are held in equilibrium by springs F², moving 40 between guide-pins *s*, which levers F operate through their connecting-pins *g* to move the levers G in turn, which, through their connecting-pins *h*, permit the levers H, which are attached to the bottom of the pressure-chamber K, to fall, which movement of the levers H allows the double-action disk-valves I to fall and close the upper ends of the tubes J, that connect the interior of the pressure-chamber K 45 with the outer air and open the lower ends of said tubes J, whereby the air-pressure from the chamber K into the bellows-valve L is cut off and the air from said bellows-valve L permitted to escape into the open air through the 50 passage L' and tube J, while the pressure in the chamber K presses upon the ribs of the bellows-valve L and collapses it, which has the effect of drawing down the bellows-valve top board, *i*, and thereby allowing the wind-pressure in the chamber K to pass through the tubes N into the organ-pipes O and cause them 55

to sound. When a perforation in the music sheet or strip D has passed a jack or lever, E, the said lever E is then raised from the corresponding push-pin, B, and the action of the connected levers and valves is reversed, so that the air-pressure is shut off from the organ-pipes O.

A bellows valve or pallet, L, consists of a small bellows formed with top and bottom boards, *i*, *k*, connected with each other by flexible leather ribs *l*. The upper side of the top board, *i*, is covered with soft leather and forms the valve, which seats close against the under side of the sound-board bar P, and it is kept in this position, when at rest, by a spring, *m*, which pushes upward from the fixed bottom board, *k*. The back or tail end of the bottom board, *k*, is hollow, as shown at *k'*, and is fitted into a mortise, *k*², in the wind-bar P', through which a channel or passage, L', is continued to the pressure-chamber K through the communicating tube J. The front end of the bottom board, *k*, is fixed sufficiently below the top board, *i*, to permit the distention of the bellows-valve L nearly or quite to its full extent. The position of the double disk-valve I determines the communication between the interior of the valve L and the pressure-chamber K and the outside air. In a position of rest the top disk, 95 *n*, is open, so that the compressed air from the chamber K is inside of as well as around the valve L, and of course by its pressure holds the top board, *i*, firmly against the sound-board bar P. When in this position the lower disk, *o*, is closed and prevents the escape of the compressed air. If the position of this disk-valve I is reversed by the lowering of a lever, H, the compressed air is at once stopped from entering the interior of the valve L, and the pressure on the outside of said valve L collapses it, with the effects hereinbefore set forth, the air from the interior of said valve L escaping through the channel L' into a tube, J, and thence into the outer air.

The pressure-chamber K is supplied with air under pressure from an air receiver or regulator, Q, that is actuated by spring *t*, and receives air from a force-pump or bellows, Q', which is provided with suitable ports and valves, *u*, the air from said receiver Q passing through a wind-trunk, Q², through the sounding-board A, into said chamber K. A horizontal bar, R, extending from the sounding-board A limits the expansion of the said receiver Q.

When it is desired to manually operate the instrument the music sheet or strip D and the jacks or levers E E are removed or elevated, so as not to affect the movement of the push-pins B B, and the keys S, which are ordinary organ-keys fixed with their inner ends in contact with the outer ends of the levers G, are manipulated in the usual manner with organ-keys.

Having thus described my invention, I claim as new and desire to secure by Letters Patent—

1. In a wind musical instrument, the combi-

nation, with a perforated music-sheet and jacks, levers, or key-moving fingers arranged on one side of it and push-pins arranged on the other side thereof, of a perforated block embracing said sheet and movable laterally, substantially as herein shown and described, whereby a lateral movement of the said music-sheet is imparted to the said push-pins, as set forth.

5. In a wind musical instrument, the combination, with a perforated music sheet or strip arranged between jacks, levers, or key-moving rods on one side and push-pins on the other side, of a laterally-movable box or frame holding said levers, jacks, or rods and embracing the edges of said sheet or strip, substantially as herein shown and described, whereby the relative lateral positions of said jacks or rods and music-sheet are preserved, as set forth.

10. In a musical instrument adapted to be played by means of a moving perforated music-sheet, which controls the operation of valves to its reeds, pipes, or other sounding devices, the combination, with the jacks or levers E, pivoted in pivoted frame E', of the movable

perforated block C, push-pins B, and connected 25 levers and wind-regulating valve F, G, H, and I, respectively, substantially as herein shown and described.

15. In a wind musical instrument, the combination, with the air-pressure chamber K, escape-tubes J, air-passages L', and pipe-connecting tubes N, of the bellows valve or pallet L, having a spring, m, and arranged within said pressure-chamber against the mouth of the tubes N, substantially as herein shown, and 30 35 for the purpose described.

20. In a wind musical instrument constructed and adapted to be operated mechanically or manually, the combination, with the air-pressure chamber K and escape-tube J, of the bellows valve or pallet L, provided with communicating supply and exhaust passage L', substantially as herein shown and described.

ALONZO DURKEE.
